RADIATOR.

1,029,468.

Specification of Letters Patent. Patented June 11, 1912.

Application filed October 21, 1911. Serial No. 655,876.

To all whom it may concern:

Be it known that I, FREDERICK SCHNEIDER, a citizen of the United States, and a resident of Fort Leavenworth, in the county of 5 Leavenworth and State of Kansas, have invented a new and Improved Radiator, of which the following is a full, clear, and exact description.

The object of the invention is to provide 10 a new and improved radiator, arranged to insure a rapid circulation of the steam, water or other fluid heating medium employed under any desired pressure, to dispense with the use of air valves or vents 15 and thus avoid leakage, to prevent the escape of bad air from the radiator into the room in which the radiator is located, and to prevent hammering.

For the purpose mentioned, use is made 20 of a series of connected radiator sections, a supply valve, a distributing pipe connected with the said supply valve and extending through the radiator sections, excepting the last one, in which the distributing pipe terminates, the said distributing pipe having 25 openings registering with the interior of the radiator sections, and a return flow pipe extending through the said distributing pipe and having one end opening into the last 30 radiator section and having the other end terminating adjacent the said valve.

A practical embodiment of the invention is represented in the accompanying drawings, forming a part of this specification, 35 in which similar characters of reference indicate corresponding parts in both views.

Figure 1 is a side elevation of the radiator, parts being in section; and Fig. 2 is a transverse section of the same on the line 40 2-2 of Fig. 1.

The radiator is provided with end sections A, A' and intermediate sections A², and the said sections are connected with each other at their lower ends by the usual nipples B, and similar nipples B' are employed for connecting the sections with each other at their upper ends. The first radiator section A is provided on its outer side with a reducing coupling C provided with a short 45 pipe C' having an enlarged head C² forming a receptacle for water and connected by a coupling D with a supply valve E, of any 50 approved construction, constructed and con-

nected by a pipe F with the steam or other heating medium supply.

Through the nipples B extends concentrically a distributing pipe G screwing at its forward end into the pipe C' of the reducing coupling C, and the other end of the distributing pipe G terminates in the last 60 radiator section A', and this end is closed by a cap G'. The distributing pipe G is provided with the distributing openings G² in the top opening into the interior of the sections A, A' and A², so that the steam or 65 other heating medium passing through the valve E and pipe C' into the pipe G can pass from the latter by way of the openings G² into the several sections A, A', A².

Through the distributing pipe G extends 70 a return flow pipe H for returning the water of condensation to the valve E and pipe F with a view to return the water to the boiler or other source of supply. The forward end H' of the return flow pipe H is bent downward in the head C² of the pipe C' so as to be water sealed by the water standing in the head C², as will be readily understood by reference to Fig. 1, to prevent the steam or other heating medium from passing into the 80 end H' of the pipe H. The rear end of the return flow pipe H extends through the cap G' so that the space between the pipes G and H is closed at the outer end. The end of the pipe H extending through the cap G' 85 opens into the end radiator section A', to permit the water of condensation to flow from this end section A' through the pipe H into the head C², and from the latter into the valve E and to the pipe F to be returned 90 to the boiler. The return flow pipe H is preferably arranged eccentrically within the distributing pipe G near the bottom thereof, and sufficient space is left between the pipes G and H to permit a ready flow of the steam 95 or other heating medium through the pipe G to pass from the latter by way of the openings G² into the radiator sections. It will also be noticed that by arranging the return flow pipe H in the manner described, 100 it is located as low as possible to keep the level of the water of condensation as low as possible in the lower portions of the radiator sections. By sealing the inner end of the pipe H, steam is prevented from freely 105 entering the radiator sections and there is

caused a jetting of the steam from the perforations G^2 of the pipe G , because the condensation of the steam due to radiated heat maintains a lower pressure in the radiator than within the pipe.

5 The pipe G extends preferably concentrically through the nipples B and sufficient space is left between the pipe G and the nipples B to allow free circulation of steam 10 from one radiator section to the other at the lower ends thereof, and at the same time allow a free circulation of the air of condensation from one radiator section to the other, the water finally being drained out 15 of the radiator from the last end radiator section A' , as previously explained. The outer face of the last radiator section A' is provided opposite the cap G' with a standard plug I , and similar plugs I' and I^2 are arranged on the outer face of the end 20 radiator sections A and A' opposite the nipples B' , so that convenient access can be had to the upper and lower portions of the radiator sections on unscrewing the said plugs 25 I , I' and I^2 . The end radiator sections A and A' are provided with the usual legs A^3 , and for radiators having many sections one or more of the intermediate sections may be provided with such legs, the same as now 30 practised.

By the arrangement described, the heating medium is readily distributed in the several radiator sections irrespective of the pressure employed, and the air valves and 35 vents are completely dispensed with to reduce leakage to a minimum and hammering is prevented as means are provided for a free escape of the water of condensation. It will further be noticed that the reducing coupling C , the distributing pipe G and the return flow pipe H can be readily placed in steam radiators as now constructed on removing the usual nipples at the bottom 40 of the radiator sections, removing the air valve and plugging up the hole. By arranging the radiator as shown and described the individual parts can be readily taken to the room or other place in which the radiator is to be used and the parts assembled there: 45 The pipes G and H arranged as described may also be introduced into radiators as now constructed without removing the nipples by simply disconnecting at valve and inserting connected pipes G and H through 50 the bushing with which the valve is usually connected.

Having thus described my invention, I claim as new and desire to secure by Letters Patent:

60 1. A radiator, comprising a series of connected radiator sections, a supply valve, a distributing pipe connected with the said supply valve and extending through the radiator sections, except the last one in 65 which the pipe terminates, the said distrib-

uting pipe having in its top openings leading into the radiator sections, and a return flow pipe extending through the said distributing pipe and having one end opening into the last radiator section and having the other end terminating adjacent the said valve and water sealed, the space between the said pipes being closed at the outer end.

2. A radiator, comprising a series of radiator sections, nipples connecting the said sections with each other at top and bottom, a distributing pipe extending through the bottom nipples and having one end closed and terminating in the last radiator section, 80 the said distributing pipe having in its top openings for discharging the heating medium into the radiator sections, a supply valve connected with the other end of the said distributing pipe, and a return flow pipe 85 extending through the said distributing pipe and opening into the last radiator section, the discharge end of the said return flow pipe being adjacent the said valve and water sealed.

3. A radiator, comprising a series of radiator sections, nipples connecting the said radiator sections with each other at top and bottom, a supply valve, a distributing pipe extending through the bottom nipples provided in its top with openings in register with the interior of the radiator sections, the terminal of the distributing pipe being within the last radiator section and being provided with a cap closing its outer end, a 100 reducing coupling connected with the first radiator section and connecting the said valve with the entrance end of the said distributing pipe, said coupling containing water to form a water seal, and a return flow 105 pipe extending through the said distributing pipe and through the said cap into the last radiator section, the other end of the said return flow pipe opening into the water seal of the said reducing coupling.

4. A radiator, comprising a series of radiator sections, nipples connecting the radiator sections with each other at top and bottom, a supply valve, a distributing pipe extending through the bottom nipples provided in its top with openings in register with the interior of the radiator sections, the terminal of the distributing pipe being within the last radiator section and being provided with a cap closing its outer end, 115 a reducing coupling connected with the first radiator section and connecting the said valve with the entrance end of the said distributing pipe, the said reducing coupling having an enlarged head for the reception of water to form a water seal, and a return flow pipe extending through the said distributing pipe and passing through the said cap into the last radiator section, the front 120 end of the said return flow pipe being bent 125 130

downward and extending into the water seal in the head of the said reducing coupling.

5. A radiator comprising a series of radiator sections having openings at top and bottom establishing communication between the sections, an enlarged head carried by the first section and adapted to be connected with a fluid supply, said head being adapted 10 to contain water to form a water seal, a distributing pipe extending through the bottom openings of the sections and having openings in its top, said pipe being connected at one end with the said head and having 15 its other end closed and terminating in

the last section of the radiator, and an open ended return flow pipe arranged in the distributing pipe with one end opening into the last radiator section, and its other end extending into the said head and bent downwardly so as to be sealed by the water in the head. 20

In testimony whereof I have signed my name to this specification in the presence of two subscribing witnesses.
